UNITED STATES PATENT OFFICE

2,041,006

METALLIC CAR DOOR

Gabriel Madland, Chicago, Ill., assignor, by mesne assignments, to The Youngstown Steel Door Company, Cleveland, Ohio, a corporation of Ohio

Application September 21, 1933, Serial No. 690,407

8 Claims. (Cl. 189—46)

This invention relates to metallic car doors. It is directed more particularly to sliding car doors adapted to be supported upon a plurality of balls for relative longitudinal movement upon 5 a side of a railway car.

It is an object of this invention to provide a sliding metallic car door having a ball runway secured thereto, said runway being of such construction and so incorporated with the panel of 10 the door as to avoid modification of said panel.

A further object is to provide a sliding metallic car door having a ball runway secured thereto in such relationship that the weight of said door is substantially centered over supporting 15 balls without the necessity of modification of said door.

A further object resides in the provision of a sliding metallic car door having a ball runway secured to the lower margin thereof, said runway being disposed in substantial symmetry relative 20 to the main plane of said door and so related to the door opening as to exclude entry of direct and reflected light between said door and the bottom of the door opening and to serve as a 25 weatherproofing member in the closed position of the door.

With these and other objects which will become clear as the description proceeds the invention comprises the novel structure and combination 30 of parts hereinafter described and more particularly pointed out and defined in the appended claims.

In the drawing forming part of this specification

35 Figure 1 is a partial elevation of a car door embodying the instant invention;

Figure 2 is a vertical section taken on line 2—2 of Figure 1;

40 Figure 3 is a horizontal section taken on line 3—3 of Figure 1, the track being removed for the sake of clearness; and

Figure 4 is a horizontal section similar to Figure 3 taken on line 4—4 of Figure 1.

Referring to the drawing which illustrates a 45 preferred embodiment of the invention there is shown a car door 10 preferably formed of metal and comprising a main sheet metal panel 11 which, as better shown in Figure 1 of the drawing, may be provided with a plurality of horizontal corrugations 12 extending between and merging 50 with vertical corrugations 13 and 14 provided in the metallic panel adjacent the vertical edges of the door.

The door is mounted for sliding movement upon 55 a track 15 secured to the side sill 16 of a railway

house car 17 by means of a plurality of brackets 18, one of which is illustrated in Figure 2 of the drawing. The door is adapted to close an opening 19 provided in the side of the car, this opening being defined in part by means of the front 5 and rear door posts 20 and 21 and the floor 22 of the car. The railway house car illustrated is of the type known as a metal sheathed car and comprises the metallic sheathing 23 secured to the posts 20 and 21, as indicated at 24 and 25. 10 An inner wooden lining 26 is utilized which at its ends is secured to a wooden nailing strip 27 disposed within the front door post and to a wooden nailing strip 28 disposed within the rear door post. The front door post, as clearly illustrated in Figure 3 of the drawing, carries an angle stop member 29 against which the front edge of the door is adapted to abut in closed position. The rear door post 21 is provided with a spark strip 30 adapted to be engaged by a sealing strip 31 secured to the 15 rear margin of the door in order to exclude sparks and the like from entering the car.

The door 10 hereinbefore described is adapted to be supported for antifrictional movement relative to the car side by means of a plurality of 20 balls. To this end there is secured to the lower margin of the door a ball runway 32 substantially Y shaped in section. The ball runway 32 carries a flange 33 which, as clearly shown in Figure 2 of the drawing, is disposed inwardly of the 25 lower margin of the metallic panel 11 and between said margin and a backing plate 34 and secured to these parts as by means of rivets 35. The upper portion of the backing plate, as is well 30 known, is secured to the metallic panel above the lower horizontal corrugation 12. A pair of diverging flanges 36 and 37 substantially coextensive with the length of the door extend downwardly from the attaching flange 33, thereby providing a runway within which the supporting 35 balls 38 are adapted to be seated. The attaching flange 33 lies substantially in the main plane of the metallic panel 11 so that the flanges 36 and 37 are disposed substantially symmetrically with 40 respect to said plane. These flanges adjacent their lower portions are bent downwardly as indicated at 39 and 40 and extend to the track 15 so as to cooperate therewith in excluding the entry of rain or foreign matter into the ball runway. It will be apparent, of course, that the flanges 45 may be extended below the track if desired. The inwardly disposed flange 36, as best shown in Figure 2 of the drawing, lies below and in proximate relationship to the floor 22 of the car or in 50 proximate relationship to a threshold plate 41 55

which preferably overlies the floor within the door opening 19 and may be extended downwardly over the edge of said floor and secured to the side sill as by means of rivets 42. By this relationship 5 between the inwardly extending flange 36 of the ball runway and the floor or threshold plate of the car it will be apparent that said flange effectively cooperates with said floor or threshold plate in precluding entry of foreign matter into the 10 car through the door opening and in excluding direct and reflected light from entering the car through the bottom of the door opening.

Reinforcing brackets 43 and 44 are secured to the lower corners of the door 10. The bracket 43 secured to the lower front corner of the door is provided with an inwardly extending wall 45, more clearly illustrated in Figure 3 of the drawing, against which the front end of the ball runway 32 abuts in order to close said end to prevent escape 20 of the supporting balls 38 therethrough. The bracket 43 is also provided with a downwardly extending flange 46 provided with a spaced upwardly extending flange 47 between which flanges a downwardly extending flange 48 provided on 25 the track 15 is adapted to be received in order to properly retain the lower portion of the door upon said track. Reinforcing ribs 49 and 50 are provided on the bracket flange 46. The rib 49, as clearly illustrated in Figure 3 of the drawing, 30 combines with an angle member 51 secured to the front vertical margin of the door to provide a substantially channel shaped member which, in the closed position of the door, coacts with the front stop angle 29 to exclude entry of the elements into the door opening. The rear reinforcing bracket 44 is quite similar in construction to the bracket 43 and is provided with an inwardly extending wall 52, better shown in Figure 4 of the drawing, adapted to close the rear end of the 40 ball runway 32. It is to be observed that the walls 45 and 52 provided, respectively, on the brackets 43 and 44, are disposed below the floor 22 of the car. The similarity of the bracket 44 to the bracket 43 is carried out further by the 45 provision of a track engaging flange 56 and the reinforcing ribs 57 and 58.

It is to be observed that the supporting balls 38 which are spaced apart a distance somewhat greater than half the length of the door are 50 maintained in such spaced relation by means of the ball spacer 59.

It will be apparent that numerous changes and modifications in the details of the invention will 55 be clear to those skilled in the art. It is intended, therefore, that all such modifications and changes be comprehended within this invention, which is to be limited only by the scope of the claims appended hereto.

60 I claim:

1. A sliding metallic car door of the character described comprising a sheet metal panel and a longitudinally extending ball runway secured to the lower margin of said panel, said runway having a vertical flange secured to said panel and downwardly diverging ball engaging flanges extending from said vertical flange, one of said flanges extending inwardly of the main plane of said panel and the other of said flanges extending similarly outwardly of the main plane of said panel, said flanges confining supporting balls for said door for rolling movement in said runway in a vertical plane corresponding substantially to the vertical plane including the center of gravity 75 of said door.

2. In a railway house car having a door opening and a track disposed upon said car below said opening, a metallic door adapted to close said opening, said door comprising a metallic panel and a metallic member secured to the lower margin thereof, said member having a plurality of downwardly diverging flanges providing a ball runway, a plurality of supporting balls seated in said runway in rolling engagement with said diverging flanges and with said track, said flanges determining the position of said balls relative to said door whereby the weight thereof is substantially centered over said balls. 5

3. In a railway house car having a door opening and a track secured to said car below said opening, a metallic door for closing said opening, said door comprising a metallic panel and a metallic member having a vertical flange secured to the lower margin of said panel, flanges extending respectively inwardly and outwardly from said securing flange to provide a ball runway, a plurality of balls seated in said runway in engagement with said inwardly and outwardly extending flanges for supporting said door for antifrictional movement upon said track, said inwardly extending flange lying below and in proximate relation to the bottom of said door opening in the closed position of said door for the purpose set forth. 10

4. In a railway house car having a door opening and a track secured to said car below said opening, a metallic door for closing said opening, said door comprising a metallic panel and a metallic member having a vertical flange secured to the lower margin of said panel, flanges extending respectively inwardly and outwardly from said securing flange to provide a ball runway, a plurality of balls seated in said runway in engagement with said inwardly and outwardly extending flanges for supporting said door for antifrictional movement upon said track, said inwardly extending flange lying below and in proximate relation to the bottom of said door opening in the closed position of said door, said metallic member being disposed substantially symmetrically with respect to the main plane of said panel. 30

5. In a railway house car having a door opening defined in part by the floor of said car and a track secured to said car below said floor, a metallic door for closing said opening, said door comprising a sheet metal panel and a ball runway secured to the lower margin of said panel, a plurality of balls seated in said runway for supporting said door for antifrictional movement upon said track, a portion of said runway extending inwardly below and in proximate vertically overlapping relation to said floor for the purpose set forth. 50

6. In a railway house car having a door opening defined in part by the floor of said car and a track secured to said car below said floor, a metallic door for closing said opening, said door comprising a sheet metal panel and a ball runway secured to the lower margin of said panel, a plurality of balls seated in said runway for supporting said door for antifrictional movement upon said track, a portion of said runway extending inwardly below and in proximate relation to said floor, said runway confining said balls substantially in the main plane of said panel during the 65 movement of said door. 70

7. In a railway house car having a door opening defined in part by the floor of said car and a track secured to said car below said floor, a metallic door for closing said opening, said door 75

comprising a sheet metal panel and a ball runway secured to the lower margin of said panel, a plurality of balls seated in said runway for supporting said door for antifrictional movement upon said track, a portion of said runway extending inwardly below and in proximate relation to said floor, said runway being disposed substantially symmetrically with respect to the main plane of said panel.

8. A sliding metallic car door of the character described comprising a sheet metal panel and a longitudinally extending member secured to the lower margin of said panel, said member being substantially of inverted Y shape in section and comprising a stem secured to said panel and integral downwardly diverging flanges, said flanges providing a ball runway for said door.

GABRIEL MADLAND.
